KNITTED FABRIC

Roger P. Guillemette, Tiverton, R.I., assignor to Fair-hope Fabrics, Inc., Fall River, Mass., a corporation of Massachusetts

Filed June 30, 1961, Ser. No. 65,769

Term of patent 14 years

(Cl. D47—2)

The FIGURE is a plan view of a knitted fabric embodying my new design with the wales running in a cross-wise direction. The fabric is of conventional thickness and is shown over a dark background to bring out the details of the design.

I claim:

The ornamental design for a knitted fabric, substantially as shown and described.
